Specification of Letters Patent.

Patented Oct. 4, 1921.

Application filed January 4, 1921. Serial No. 434,930.

To all whom it may concern:

Be it known that I, JEAN BAPTISTE COTTARD, citizen of the Republic of France, resident of Paris, France, have invented new and useful Improvements in Semidiesel Oil-Engines, which invention is fully set forth in the following specification.

It has not been possible hitherto to use coal oil regularly as a fuel in Diesel and 10 semi-Diesel engines.

In Diesel engines coal oil can be used alone for from half-load to full load; but below half-load it is absolutely necessary to add petroleum or igniting oil to the coal 15 oil; the starting being effected by means of petroleum.

In order to get semi-Diesel engines to run satisfactorily under any load; it is necessary to add igniting oil to the coal oil.

20 The present invention has for its object to provide a combination of means whereby semi-Diesel engines can be started, and made to run idle, and at their various speeds exclusively by means of coal oil without the 25 addition of any other fuel.

According to this invention the engine cylinder (as illustrated in vertical section in Figure 1 of the accompanying drawings) comprises a cylinder head chamber B, not 30 cooled, communicating with the cylinder proper A by means of a narrow passage b, at a place where the piston never comes. This cylinder head chamber B is followed by an ignition chamber C with which it is in 35 communication by means of a passage c of smaller diameter than the passage b. This construction allows of almost wholly avoiding the scavenging of the cylinder head chamber, and of retaining in the latter a 40 portion of the exhaust gases at a very high temperature.

This means is combined with the use of an injecting twyer D supplying a jet whose inclination, shape and location must be so 45 chosen as to assure that the point d of axial impact, as also the spread of the jet shall be such that the injected liquid will always be confined in the interior of the top of the cylinder head chamber B.

50 The injection of the fuel is effected in two stages:—A first portion of the liquid fuel of relatively small amount, is injected at the bottom dead center of the piston stroke or in the vicinity of this dead center. Since 55 only a small quantity of liquid fuel is

admitted in this manner, the said liquid fuel will be vaporized before coming into contact with the walls of the cylinder head chamber B, and therefore will not cool the chamber B which would otherwise occur if the whole 60 of the required fuel were injected at once in the usual way.

The liquid fuel thus injected is ignited however just before the piston reaches its top dead center, by the combined action of 65 the temperature of the cylinder head chamber and of the compression, and it is this first portion of the fuel admitted in this manner that assures the ignition of the main quantity of the liquid fuel which latter is 70 injected at the moment when the piston has reached its top dead center or a few degrees before the piston does reach this dead center.

This distribution may be effected by any 75 suitable mechanism.

For instance, as illustrated diagrammatically in Fig. 2, there may be mounted on a shaft E driven from the engine shaft, a cam F having two prominences f, f¹ arranged at diametrically opposite points. 80 These prominences, f, f¹, which have suitable shapes, act at the desired time upon a roller g carried by the arm G of a bellcrank lever G—G¹ fulcrumed at a fixed point g¹, and also carrying at the apex of its angle a 85 roller G² by means of which it acts upon the free end of the piston rod H of the injecting pump.

The shapes of the prominences f and f¹ are suitably designed for injecting the 90 desired relative quantities of liquid fuel, at the moments of arrival of the piston at its lower dead center and upper dead center respectively. The greater part of the liquid fuel is injected by the action of the operating prominence f¹ at the moment the piston arrives at its upper dead center; this injection being effected at a high speed.

Having now particularly described and ascertained the nature of my said invention 100 and in what manner the same is to be performed, I declare that what I claim is:

In an internal combustion engine of the Diesel type, the combination of an engine cylinder having a non-cooled cylinder head 105 chamber open to said cylinder through a narrow passage, an ignition chamber open to said cylinder head chamber through a passage of smaller cross-section than said first named passage, means for injecting 110

liquid fuel at such inclination and thickness of jet as will confine the injected liquid in the interior of the upper portion of said cylinder head chamber, fuel-distributing means controlling said injecting means whereby fuel is injected in two stages and of unequal amounts, the first of which stages taking place about the lower dead center of the piston stroke to introduce the

smaller igniting charge to be ignited by accumulated heat in said ignition chamber and the second of which taking place at or near the upper dead center of the piston stroke to introduce the working charge to be ignited by said ignition charge. 10

In testimony whereof I have signed this specification. 15

JEAN BAPTISTE COTTARD.
